LOCKING HINGE FOR SEAT STRUCTURE

Elmer A. Herider, Dearborn Township, Mich., assignor
to Rockwell Spring and Axle Company, Coraopolis, Pa.,
a corporation of Pennsylvania

Application October 3, 1955, Serial No. 38,204

Term of patent 14 years

(Cl. D15—8)

Figure 1 is a perspective view of a locking hinge for seat structure, showing my new design;

Figure 2 is a front elevational view thereof; and

Figure 3 is a top plan view thereof to an enlarged scale.

The dotted line disclosure of the seat structure of Figure 1 is shown only for the purpose of illustration.

I claim:

The ornamental design for a locking hinge for seat structure, as shown and described.
